DESIGN FOR A COMBINED MOTOR DRIVEN AGITATOR AND SUPPORT FOR DAIRY APPLIANCES OR ANALOGOUS ARTICLES

Charles B. Whiteside, Birmingham, Ala.

Application June 26, 1940, Serial No. 93,247

Term of patent 7 years

To all whom it may concern:

Be it known that I, Charles B. Whiteside, a citizen of the United States of America, residing at Birmingham, in the county of Jefferson and State of Alabama, have invented a new, original, and ornamental Design for a Combined Motor Driven Agitator and Support for Dairy Appliances or Analogous Articles, of which the following is a specification, reference being had to the accompanying drawing, forming part thereof.

In the drawing:

Fig. 1 is a plan view showing my new design for a combined motor driven agitator and support for dairy appliances or analogous articles.

Fig. 2 is a side elevational view of same; and
Fig. 3 is a front view of same.

I claim:

The ornamental design for a combined motor driven agitator and support for dairy appliances or analogous articles, as shown.

CHARLES B. WHITESIDE.
